UNITED STATES PATENT OFFICE.

ARTHUR J. LUSH, OF CAMBRIDGE, MASSACHUSETTS, ASSIGNOR TO RAWSON ELECTRICAL INSTRUMENT COMPANY, OF CAMBRIDGE, MASSACHUSETTS, A CORPORATION OF MASSACHUSETTS.

BINDING POST.

Application filed January 19, 1920. Serial No. 352,433.

To all whom it may concern:

Be it known that I, ARTHUR JOHN LUSH, a subject of the King of Great Britain, and a resident of Cambridge, in the county of 5 Essex and Commonwealth of Massachusetts, have invented a new and useful Improvement in Binding Posts, of which the following is a specification.

The present invention relates to binding 10 posts, and more particularly to posts the clamping caps of which are readily freely movable, but in which provision is made for preventing the cap falling off the clamping post and becoming lost.

15 The object of the invention is to provide an improved binding post of the above-described character which shall be simple in construction, cheap to manufacture and efficient in operation.

20 With this end in view, a feature of the invention resides in providing the clamping post with an enlarged end that is adapted to lie normally in an enlarged chamber of the cap. From the chamber leads a reduced 25 bore within which normally lies the body of the clamping post and the walls of which are adapted to bind upon the enlarged end to render difficult the removal of the cap.

To the attainment of the above-named object, the invention consists of the improved 30 binding post hereinafter described, illustrated in the accompanying drawings and defined in the appended claims.

In the drawings, Fig. 1 is a view in elevation of a clamping post constructed in accordance with the present invention; Fig. 2 is a similar view, showing the enlarged end lying within the reduced bore of a clamping cap; Fig. 3 is a view similar to Fig. 2, showing the enlarged end of a modified clamping post positioned within the enlarged chamber of the cap; and Figs. 4, 5 and 6 are views of modifications.

The clamping post of the present invention is threaded at 2 and 4 and is provided 45 with an intermediate clamping element 6 about which, and about a portion 8, is molded a boss 10 of insulating material. The threaded portion 2 is adapted to enter 50 an opening in a panel (not shown) so that the boss 10 may rest upon the face thereof, and the post may be secured in such position upon the panel by a nut threaded upon the portion 2.

A cap 12 is provided with an enlarged 55 chamber 14 and a reduced bore 16 leading therefrom, within which bore is adapted to lie the portion 4 of the clamping post. The reduced bore 16 is preferably threaded and the portion 4 is provided with threads 60 adapted to cooperate with the threads of the bore. The body of the terminal portion 4 is of less diameter than the diameter of the bore 16, as is shown more particularly in Fig. 3, so as to provide an easy fit. The cap 65 may thus be readily freely rotated upon the clamping post to move the clamping element 18 into and out of engagement with the clamping element 6. To prevent the cap falling off the clamping post by continued 70 free movement thereof upon the post, the end 20 is enlarged to such diameter that the said end may bind lightly upon the walls of the reduced bore, as shown in Fig. 2, and thus, though not preventing the removal of 75 the cap, render such removal difficult. The easy or accidental removal of the cap from the clamping post is therefore prevented, though the removal may be effected by sufficient turning pressure exerted upon the cap 80 12. The enlarged end 20, which is preferably, though not necessarily, threaded, lies normally in the enlarged chamber 14, the walls of which it can not engage, so that a limited degree of free movement of the cap 85 is thus provided for.

The end 20 may be enlarged in any desired manner. A convenient method of enlarging the end is to slot it to form a fork, expand the prongs 22 of the fork, and wedge 90 material into the space provided between the prongs. The space between the prongs may, if desired, be filled with a metal in liquid condition, like solder 24, which is then allowed to solidify. It is found, in practice, 95 usually, that neither the wedge nor the filling material is necessary, the process of expanding imparting a set to the prongs which is sufficient for ordinary purposes.

As the end 20 of the binding post may 100 be inserted into the chamber 14 through the reduced bore 16, it is not essential that the chamber 14 be open, as has been the case with certain types of binding posts hitherto employed. The advantages of the 105 closed-chamber cap may thus be obtained, according to the present invention, in combination with a clamping post the end of

which is expanded. To the attainment of this result, the chamber may be closed by a plate 26, after which an insulating covering 28 may be molded thereabout and about 5 the base 30 upon which it is positioned.

In some cases, it is desirable that the cap be permanently secured to the clamping post so as not to be removable therefrom. One method of bringing about this result in accordance with the present invention is illustrated in Figs. 4 and 5. A wedge 32 may be partly inserted between two or more prongs 22 before the end 20 is threaded through the reduced bore 16. Upon sufficiently continued rotation of the clamping post, the end of the wedge 32 will engage the inner face of the plate 26, and further rotation of the clamping post will force the wedge into the space between the prongs, causing the prongs to expand to such degree as to prevent the removal of the clamping post through the bore 16.

It will be understood that the invention is not limited to the exact embodiments thereof herein illustrated and described, but that it is susceptible to modification within the spirit and scope of the appended claims.

What is claimed as new is—

- 30 1. In combination, a cap having a closed chamber and a reduced bore leading from the chamber, and a post in the bore the body of which is of cross dimension less than the cross dimension of the bore and having means normally positioned in the chamber of such dimension as to adapt the said means to bind lightly upon the walls of the bore without preventing the removal of the cap from the post, a portion of the 35 body of the post being also normally positioned in the chamber, whereby the cap is freely movable along the said portion of the body of the post but is restricted against free movement when the said means binds 40 against the walls of the bore, the cap being adapted to be applied to the post and removed from the post by the application of a force sufficient to overcome the binding action of the said means against the walls 45 of the bore.
- 50 2. A binding post comprising a clamping

cap having a closed chamber and a reduced threaded bore leading from the chamber, and a cooperating threaded clamping post threaded in the bore the body of which is 55 of diameter less than the diameter of the bore and having a threaded end normally positioned in the chamber of such diameter as to adapt the said end to bind lightly upon the threaded walls of the bore without preventing the removal of the cap from the post, a portion of the body of the post being also normally positioned in the chamber, whereby the cap is freely threaded 60 movable along the said portion of the body of the post but is restricted against free movement when the said end binds against the walls of the bore, the cap being adapted to be applied to the post and removed from the post by the application of a force sufficient to overcome the binding action of the 65 said end against the walls of the bore.

3. A binding post comprising a clamping cap having a closed chamber and a reduced threaded bore leading from the chamber, and a cooperating threaded clamping post threaded in the bore the body of which is 70 of diameter less than the diameter of the bore and having an expanded threaded forked end normally positioned in the chamber of diameter greater than the diameter of the body of the post, the said diameter being such as to adapt the said end to bind lightly upon the threaded walls of the bore without preventing the removal of the cap 75 from the post, a portion of the body of the post being also normally positioned in the chamber, whereby the cap is freely threaded 80 movable along the said portion of the body of the post but is restricted against free movement when the said end binds against the walls of the bore, the cap being adapted to be applied to the post and removed from the post by the application of a force sufficient to overcome the binding 85 action of the said end against the walls of the bore.

In testimony whereof, I have hereunto subscribed my name this 17th day of January, 1920.

ARTHUR J. LUSH.
